(57) **CLAIM**

The ornamental design for an egg container, as shown and described.

DESCRIPTION

FIG. 1 is a front, top perspective view of an egg container, showing my new design;

FIG. 2 is a front, bottom perspective view thereof;

FIG. 3 is a rear, bottom perspective view thereof;

FIG. 4 is a front elevational view thereof, the rear elevational view being a mirror image of FIG. 4;

FIG. 5 is a left side view thereof;

FIG. 6 is a right side view thereof;

FIG. 7 is a top plan view thereof;

FIG. 8 is a bottom plan view thereof;

FIG. 9 is a front, top perspective view of the egg container in a detached state; and,

FIG. 10 is a partial enlarged view of FIG. 9.

The dashed broken lines in the figures are for the purposes of illustrating portions of the egg container, which form no part of the claimed design.

The short-short-long broken lines in the figures are for the purposes of illustrating unclaimed boundaries which form no part of the claimed design.

The dash-dot-dash broken lines are for notating enlarged views, and form no part of the claim design.

The dashed broken lines in the figures are for the purposes of illustrating portions of the egg container, indicating the usage environment.
